UNITED STATES PATENT OFFICE.

WILLIAM C. HUSS, OF CINCINNATI, OHIO.

DESIGN FOR A SALES-COUNTER.

SPECIFICATION forming part of Design No. 23,706, dated October 16, 1894.

Application filed June 3, 1893. Serial No. 476,523. Term of patent 3½ years.

To all whom it may concern:

Be it known that I, WILLIAM C. HUSS, a citizen of the United States, and a resident of Cincinnati, in the county of Hamilton and State of Ohio, have invented a certain new and useful Design for a Sales-Counter, of which the following is a specification.

My invention is a new and original design for sales counters.

10 The distinguishing features of the design are the skeleton frame, the columns and intermediate scroll work in front of the case, and the heavy pillar at one end of the case, as shown in the accompanying drawing, which 15 is a perspective view of a sales counter constructed according to my design.

The frame work of my counter, as shown in the accompanying drawing, is formed by vertical upright "a" at the rear, apparently 20 resting upon the base *b*, and uprights *a'* inclined from the top to the base, which is much narrower than the top. At each end inclined intermediate uprights *a''*, which together form the inclined front of the counter and lock the 25 vertical upright "a" at the rear, rest upon the molded base *b* and apparently support the upper rectangular frame *c*.

The bottom of the counter is a shelf "d," which is on a level with the upper edge of 30 the base *b*. There is also the shelf "e" closing the lower or closet portion of the counter and forming the bottom of the upper or showcase compartment. The edges of the shelf at the ends and front of the counter are 35 enriched by a scroll molding *f*, which extends entirely around it and is formed of dark material, to form a pleasing contrast to the lighter frame work of the counter.

In front of the counter, and resting upon 40 the floor, are a number of vertical columns *g*, the bases *g'* of which stand some distance in front of the base *b*. The top of the column

terminates in globes *g''*, which apparently are part of the front top rail of the counter. The front and ends of the frame work of the 45 counter are panels, except the central panel, which is formed of varied colors, with an ornamental scroll "h" forming the center of this panel, which may be ornamented with a monogram or other suitable device. The doors 50 "i," which close the top of the sales case, are also formed of light frame work filled with panels *i'*. The upper edge of the base *b*, is molded or beveled, as shown, and the space between the upright stiles of the counter 55 and the columns is filled by ornamental scroll brackets "j," which, for the purpose of forming a pleasing contrast to the panels and polished base, are to be made of dark material, to correspond with the molding *b* and 60 the columns *g*.

At one end of the counter is a heavy pillar *K*, the body of which is substantially rectangular in form and inclines from the upper ornamented portion of the top narrower toward its base *k*. Just above the base, the column curves outward to the beveled fillet that registers with the molded top of the counter base "b," which forms the upper finish of the base *k*. The upper portion of 70 the pillar terminates in an abruptly rounded surface enriched with carved scroll work. From the center of the pillar projects upwardly an ornamental shaft having scroll branches, from the scroll portion of which 75 depend globes, and the center shaft terminates in a globed finial.

What I claim is—

A design for sales counters substantially as shown and described.

WILLIAM C. HUSS.
